England, assignors to William Cotton Limited,
Loughborough, Leicestershire, England

Application May 16, 1941, Serial No. 393,810
In Great Britain November 13, 1939

5 Claims. (Cl. 66—110)

This invention is for improvements in Cotton's patent and other straight bar knitting machines, and is concerned with the draw or Coulier mechanism therein. Its object is to provide draw or Coulier mechanism which is more robust and smooth in operation than the mechanisms heretofore used.

This invention provides in a Cotton's patent or other straight bar knitting machine, Coulier or draw mechanism comprising the draw cam, a member guided for rectilinear movement and reciprocated thereby, a second reciprocatable member guided for rectilinear movement in a path parallel to that of the first member, a draw lever for transmitting reciprocating movement from the first member to the second, which lever is arranged to oscillate about an axis which is normal to the rectilinear paths of movement of the two said members, and two cross head devices one for connecting each reciprocatable member to the draw lever. By a cross-head device there is meant a device for transforming reciprocating motion of one part into oscillatory or curvilinear motion of another part, or vice versa, and comprising an element occupying a fixed location on the one part but reciprocating in or on a suitable guide or guides in or on the other part. In the preferred construction the said element comprises a pivotally mounted slide block capable of reciprocating on suitable guiding means in a direction which is transverse to the direction of reciprocation of the two members aforesaid.

Preferably the aforesaid element or guide block is, in each device, secured to the draw lever and is arranged to reciprocate in or on suitable guide means provided on the associated reciprocatable member.

In order that the invention may be better understood a preferred construction embodying it will now be described in detail by way of example, with reference to the accompanying drawings, in which

Figures 1 and 1A together show an elevation of the mechanism;

Figure 2 is a cross sectional view, partly in elevation, taken approximately on the plane indicated by the line 2—2 of Fig. 1, looking in the direction of the arrows;

Figure 3 is a section of a detail thereof, taken on the line 3—3 in Fig. 2; while

Figure 4 is a sectional elevation of a further detail.

The accompanying drawings show only the Coulier or draw mechanism, since it is only with

this mechanism that the invention is concerned and the remainder of the machine is well understood in the art.

In the illustrated construction the draw cam 10 is, as usual, mounted on a horizontal cam shaft 11 which extends transversely of the length of the machine; it reciprocates a horizontal draw bar 12 which extends lengthwise of the machine, and is so designed as to impart constant acceleration and deceleration to said draw bar. The latter is guided nearer each end between upper and lower rollers 13, 14 which are adjustable by means indicated at 31 to take up wear and to prevent play, and it is provided with two other rollers or cam trucks 15, 16 which engage the periphery of the draw cam 10 at diametrically opposed points, the axis of rotation of said cam 10 and the axes of the said trucks 15, 16 being in one and the same horizontal plane. These trucks 15, 16 are adjustable by means indicated at 30 towards and away from each other on the draw bar 12 to take up wear and to obviate play.

Pivotedly mounted on a horizontal pivot spindle 17 there is an upstanding draw lever 18. This pivot spindle 17 is securely mounted in a robust bracket 19 attached to one of the longitudinal frame members or beams 20 of the machine and its axis is immediately below and in the same vertical plane as the axis of the draw cam 10.

The draw lever 18 is driven from the draw bar 12 by a cross-head device. This device comprises a slide block 21 which is pivotally mounted upon a horizontal pivot pin 22 secured to and projecting from one face of the draw lever 18 towards the draw bar 12, and this slide block 21 is received and guided in a vertical guide slot 23 provided midway in the length of the draw bar 12. Thus, as the draw bar 12 reciprocates, the draw lever 18 is caused to oscillate, in which movements the slide block 21 rocks upon its pivot 22 and slides up and down in the guide slot 23. The rubbing faces of the slide block 21, or of the slot 23, are provided with brasses or other anti-friction means.

At its upper end the draw lever 18 is connected by means of a similar cross-head device (comprising a block 21' having a pivot 22' and working in vertical slot 23', see Fig. 3) to a box 24 which is mounted for reciprocating movement upon a horizontal guide bar 25 which is directly above and parallel with the draw bar 12. As before, in this second cross-head device the slide block 21' is pivoted on the draw lever 18 and the vertical slot 23' in which it slides is provided in the reciprocatable box 24. The guide bar 25

is supported from a longitudinal frame member 26.

As a result of this mechanism the constant acceleration reciprocatory movements of the draw bar 12 are converted into like movements of the box 24. This box 24 is connected to the slur cock tie bar or to a thread carrier driving rod, or to both, and in a multi-division machine such for example as a multi-division full-fashioned stocking machine, there may be one draw mechanism as hereinbefore described for driving the slur cocks and another similar mechanism for driving thread carriers. Thus in Fig. 2 the block 24 of one draw mechanism is connected both to the slur cock tie bar 29 and to a driving rod or friction bar 27 for the splicing or plating carriers, while in Fig. 4 the block 24 of a like draw mechanism is shown as connected to the main carrier driving bar 28 only.

Alternatively there may be a single draw mechanism for driving the slur cock or cocks, a plating carrier or carriers, and the main carrier or carriers.

In a further alternative there are three of the draw mechanisms, one for driving the slur cock or cocks, a second for driving the main carrier or carriers, and a third for driving a plating carrier or carriers.

We claim:

1. In a Cotton's patent or other straight bar knitting machine, Coulier or draw mechanism comprising a draw cam, a member guided for rectilinear movement and thereby, a second reciprocatable member guided for rectilinear movement in a path parallel to that of the first member, a draw lever for transmitting reciprocating movement from the first member to the second, which lever is arranged to oscillate about an axis which is normal to the rectilinear paths of movement of the two said members, and two cross head devices one for connecting each reciprocatable member to the draw lever, and each comprising guide means on one of the two said parts to be connected together, and an element normally occupying a fixed location on the other of the two said parts and reciprocatable along said guide means.

2. In a Cotton's patent or other straight bar knitting machine, Coulier or draw mechanism comprising a draw cam; a member guided for rectilinear movement and reciprocated thereby; a second reciprocatable member guided for rectilinear movement in a path parallel to that of the first member; a draw lever for transmitting reciprocating movement from the first member to the second, which lever is arranged to oscillate about an axis which is normal to the rectilinear paths of movement of the two said members; and two cross head devices, one for connecting each reciprocatable member to the draw lever, each of

which cross head devices comprises guide means on one of the two parts to be connected together, extending in a direction transverse to the direction of reciprocation of the two said reciprocatable members, a slide block reciprocatable along said guide means, and means pivoting said block to the other of the two said parts.

3. Mechanism according to claim 2, wherein the guide means are carried by the respective reciprocatable members, and the slide blocks are secured to the draw lever for co-operation with the respective guide means.

4. In a Cotton's patent or other straight bar knitting machine, Coulier or draw mechanism comprising a draw cam; a draw bar reciprocatable thereby; means guiding said draw-bar for rectilinear movement; a pair of trucks on the draw-bar engaging the draw-cam at substantially diametrically-opposed locations; a draw

lever extending transversely of the line of movement of the draw bar; a pivot for the draw lever; a cross head mechanism for connecting the draw bar to the draw lever and for transforming reciprocation of the former into oscillation of the latter; a reciprocatable member driven by the draw lever; guide means for guiding said member in a rectilinear path parallel to that of the draw bar; and a second cross head mechanism for connecting the draw lever to said member and for

transforming oscillation of the draw lever into reciprocation of said member, each of which mechanisms comprises guide means on one of the two aforesaid parts which it connects together, extending in a direction transverse to the direction of reciprocation of the draw bar, and an element on the other one of the two said parts reciprocatable along the last said guide means.

5. In a Cotton's patent or other straight bar knitting machine, Coulier or draw mechanism comprising a constant acceleration draw cam; a member guided for rectilinear movement and reciprocated thereby; a second reciprocatable member guided for rectilinear movement in a path parallel to that of the first member; a draw lever for transmitting reciprocating movement from the first member to the second, which lever is arranged to oscillate about an axis which is normal to the rectilinear paths of movement of the two said members; and two cross head devices one for connecting each reciprocatable member to the draw lever, and each comprising guide means on one of the two said parts to be connected together and an element normally occupying a fixed location on the other of the two said parts, and reciprocatable along said guide means, which two elements are both provided on one and the same part.

GEORGE WILDERS.

WILLIAM GORDON MACDONALD.

CERTIFICATE OF CORRECTION.

Patent No. 2,271,381.

January 27, 1942.

GEORGE WILDERS, ET AL.

It is hereby certified that error appears in the printed specification of the above numbered patent requiring correction as follows: Page 2, first column, line 33, claim 1, before "thereby" insert --reciprocated--; and that the said Letters Patent should be read with this correction therein that the same may conform to the record of the case in the Patent Office.

Signed and sealed this 10th day of March, A. D. 1942.

Henry Van Arsdale,
Acting Commissioner of Patents.
